UNITED STATES PATENT OFFICE

131,322

DESIGN FOR A TRAILER

Battista A. Vietti, Reno, Nev.

Application August 26, 1939, Serial No. 86,900

Term of patent 14 years

To all whom it may concern:

Be it known that I, Battista A. Vietti, a citizen of the United States of America, residing at Reno, in the county of Washoe and State of Nevada, have invented a new, original, and ornamental Design for a Trailer, of which the following is a specification, reference being had to the accompanying drawing, forming a part thereof.

Fig. 1 is a perspective view of a trailer, showing my new design;

Fig. 2 is a front perspective view thereof; Fig. 3 is a rear elevational view thereof; and Fig. 4 is a top plan view thereof, with the canopy portion omitted in order to disclose more fully the interior portions of the trailer.

I claim:

The ornamental design for a trailer, substantially as shown.

BATTISTA A. VIETTI.
